UNITED STATES PATENT OFFICE.

MICHAEL J. DACY, OF RICHMOND, VIRGINIA, ASSIGNOR OF ONE-THIRD TO CLAUDE B. DAVIS AND ONE-THIRD TO JOHN T. PALMATARY, BOTH OF RICHMOND, VIRGINIA.

SHIPPING-CRATE.

1,271,285.

Specification of Letters Patent.

Patented July 2, 1918.

Application filed November 1, 1916. Serial No. 128,990.

To all whom it may concern:

Be it known that I, MICHAEL J. DACY, a citizen of the United States, residing at Richmond, in the county of Henrico, State of Virginia, have invented certain new and useful Improvements in Shipping-Crates; and I do hereby declare the following to be a full, clear, and exact description of the invention, such as will enable others skilled in the art to which it appertains to make and use the same.

This invention relates to shipping boxes or crates, and particularly to folding boxes or crates for shipping purposes.

The object of the invention is to provide an improved form of folding crate which is particularly adapted for shipping bread and similar perishable products, thereby meeting an increasing demand for a suitable hamper or other receptacle which may be collapsed and securely packed for return shipment to a point of distribution after the contents has been removed. In such a crate it is necessary that the contents be properly protected in transit, and also that the receptacles in which the goods are shipped may be of such a light character that when the crate is folded it will provide only a compact unitary parcel without undue bulk or weight.

More particularly, the invention resides in the provision of a box or crate which may be folded so as to be wholly contained within the lid as a packing receptacle and is therein secured by the same elements which are employed to set the box up.

With the above objects in view and such others as will hereinafter appear, my invention will now be fully set forth and described, reference being had to the accompanying drawings:—

In the drawings:—

Figure 1 is a perspective view of the box set up with the lid applied thereto,

Fig. 2 is a similar perspective view of the upper part of the box with the lid removed,

Fig. 3 is a vertical longitudinal section through the box,

Fig. 4 is a vertical transverse section through a corner fastening means,

Fig. 5 is a section on line 5—5 of Fig. 4,

Fig. 6 is a view of the box in folded and packed position, and

Fig. 7 is a fragmentary view showing a corner fastening.

Referring more particularly to the drawings, 1 represents a base which may be a paneled or built up structure having the marginal cleats 2. Hinged to the opposite ends of the base 1 are the end pieces 3 and 4, the end piece 3 being hinged directly to the base or bottom 1 so as to swing inwardly thereupon and the end piece 4 being mounted upon the transverse cleat 5 which extends across the end of the box and is of sufficient height to permit the end piece 4 to fold flat upon the end piece 3. The end pieces 3 and 4 are also adapted to swing into folded position between the longitudinal cleats 6 and 7, upon which are mounted the sides 8 and 9. The side 8 being adapted to fold flat upon the inwardly folded end piece 4, since the cleat 6 which supports it is equal to the thickness of the two end pieces when they are folded one upon the other. The cleat 7 is equal in height to the thickness of the three elements 3, 4 and 8, so that the side 9 carried by the cleat 7 may be folded flat upon the upper face of the side 8. Thus, when the box is collapsed, the four vertical elements thereof rest one upon the other with their outside dimensions located entirely within the limits of the outside dimensions of the base or bottom 1. The sides 8 and 9 and the end pieces 3 and 4 are preferably constructed of framed elements consisting of the horizontal frame pieces 10 and the vertical frame pieces 11 to, or behind which the backing 12 is secured, the backing 12 being formed of compo board or any other light and strong material.

The cover portion of the box consists of a box-like structure which is adapted to fit over the outsides of the end pieces and the sides, and consists of the comparatively deep sides 13, the ends 14, and the top section 15. The sides 13 and ends 14 are of such depth that when the box is folded, the lid may be inserted over the latter to wholly contain its parts, the lower face of the bottom or base 1 lying flush with the free edges of the ends 14 and sides 13.

Passing through the sides 13 adjacent the opposite ends thereof, are the apertures 16 which register with similar apertures 17 formed through the vertical margins of the box sides 8 and 9 and the vertical cleats or

frame pieces 11 of the end pieces 4. These registering apertures, when the box is set up and the lid applied, provide passageways for the reception of tie rods 18. The tie rods 18 are passed through socket plates 19 recessed in the side of the lid, and thence through the sockets or apertures 16 and 17 in the sides and ends respectively, and upon the opposite side of the lid are threaded into socket plates 20 recessed therein. At this point it should be noted that the two tie rods 18 not only lock the lid in place, but firmly and rigidly join the sides and ends to one another and prevent any possible collapsing of the box. The tie rods 18 are provided with rings 21 which pivotally engage the heads of the tie rods, so as to fall against the side of the box when not in use, but provide a means for readily manipulating the rods in order to remove or insert them. The socket plates 20 are provided upon opposite sides of their threaded openings with the lugs 22, which are apertured to correspond with a similar opening formed in the threaded end 25 of each of the tie rods, so that a sealing wire may be passed therethrough, thereby preventing unauthorized handling of the contents of the box. In order to temporarily hold the end pieces 3 and 4 and the sides 8 and 9 in set-up position while the box is being packed, I provide the hooks or similar fastening devices 24 upon the upper edges of the sides and ends so as to hook across the adjacent corners thereof, these devices imparting sufficient rigidity to the box to hold it until the lid can be applied. Preferably the socket plates 19 and 20 are corner fittings which overlie the ends, sides and free edges of the latter.

40 When the box is folded, and the body thereof is housed within the lid, apertures 25 in the marginal cleats of the bottom register with apertures 26 in the edges of the sides of the lid, so that the tie rods 18 which were removed before the box was collapsed, may be inserted therethrough in order to lock the collapsed box within the lid. Bearing plates 27 recessed within the outer face of one side of the lid provide seats for the heads of the tie rods, and the plates 28 upon the opposite side have threaded apertures within which the threaded ends of the tie rods may be inserted. Lugs 29 adjacent the threaded apertures of the plates 28 provide

for the protection of the projecting threaded ends of the tie rods.

From the foregoing description, it is evident that I have provided a very compact and serviceable shipping crate which is not only capable of withstanding the wear and tear of railroad shipment when loaded or packed, but may also be returned as "empties" without the usual danger to non-collapsible empty cases or to collapsible receptacles which are not properly secured. The device is capable, furthermore, of economical manufacture, since its requirements for fittings is reduced to a minimum, the same elements which lock the device in set-up position and secure the lid to the box also serving to secure the device in packed or collapsed condition.

What I claim as my invention is:—

1. A folding crate comprising in combination, a base having bottom cleats around its margin ends foldable upon the base, to lie within the marginal limits of the latter, sides foldable flat on the ends, a lid having side members of sufficient depth to wholly receive the folded box, and tie rods passed through the lid and the cleats of the base so as to pass across the base below its inner surface to secure the crate in folded condition, said sides, ends and the lid being also constructed to receive the tie rods when the box is set up to lock it in extended condition.

2. A folding crate comprising in combination, a base having marginal cleats, sides and ends foldable upon the base, to lie within the marginal limits of the latter, said sides, ends and base also having marginal cleats, a lid having side members of sufficient depth to wholly receive the folded box, and tie rods passed through the lid and through the bottom cleats so as to pass below the inner surface of the base, to secure the parts when in folded condition, and the cleats of the sides and ends having apertures to receive the tie rods in conjunction with the lid when the box is set up.

In testimony whereof, I affix my signature, in the presence of two witnesses.

MICHAEL J. DACY.
